UNITED STATES PATENT OFFICE

138,116

DESIGN FOR A HOLDER FOR NARROW FABRICS

Edward Funke, Pelham Manor, N. Y.

Application February 4, 1943, Serial No. 109,448

Term of patent 7 years

(Cl. D74—1)

To all whom it may concern:

Be it known that I, Edward Funke, a citizen of the United States, residing in the city of Pelham Manor, county of Westchester, and State of New York, have invented a new, original, and ornamental Design for a Holder for Narrow Fabrics, of which the following is a specification, reference being had to the accompanying drawing, forming a part thereof.

Figure 1 is a perspective view of a holder for narrow fabrics, showing my design.

Figure 2 is a side view of the holder for narrow fabrics, shown in Figure 1.

Figure 3 is a front view of the holder for narrow fabrics, shown in Figures 1 and 2.

The essential features of my design for a holder for narrow fabrics, having the specific configuration as shown, reside in the combination of four features—namely, a flat top or summit, round portions on both sides of this top, steps at the end of the rounded portions, and vertical surfaces following these steps.

I claim:

The ornamental design for a holder for narrow fabrics, as shown and described.

EDWARD FUNKE.
